AIRPLANE

Theodore R. Smith, 2444 Wilshire Blvd.,
Santa Monica, Calif.

Filed May 6, 1964, Ser. No. 79,851

Term of patent 14 years

(Cl. D71—1)

FIG. 1

FIG. 2

FIG. 3

FIG. 4

FIG. 5

FIG. 6

FIGURE 1 is a perspective view of an airplane, showing my new design;

FIGURE 2 is a side elevational view thereof showing the side not visible in FIGURE 1;

FIGURE 3 is a front elevational view thereof;

FIGURE 4 is a rear elevational view thereof;

FIGURE 5 is a top plan view thereof; and,

FIGURE 6 is a bottom plan view thereof.

I claim:

The ornamental design for an airplane, substantially as shown.
